UNITED STATES PATENT OFFICE.

JAMES HOAGLAND AND BARNHARD ZIPFEL, OF TOLEDO, OHIO.

SOAP.

SPECIFICATION forming part of Letters Patent No. 314,447, dated March 24, 1885.

Application filed January 8, 1885. (No specimens.)

To all whom it may concern:

Be it known that we, JAMES HOAGLAND and BARNHARD ZIPFEL, citizens of the United States, residing at Toledo, in the county of Lucas and State of Ohio, have invented certain new and Useful Improvements in Soap Compounds, of which the following is a specification.

Our invention relates to improvements in washing compounds or soap, and is designed to produce a compound for use in washing that shall remove all dirt and stains.

The compound consists of the following ingredients, mixed in about the proportions given, though not confined to the same, as different qualities of soap or other causes would necessitate a change of the said proportions: For one hundred pounds of soap is used twenty-two pounds of tallow, twenty-two pounds of sal-soda, (carbonate of soda,) fourteen pounds of resin, one quart of milk, one lemon, one pound of soapstone, and water of lime formed by slaking five pounds of lime in twenty quarts of water free from salts, commonly known as "soft water." The addition of the milk clarifies the soap and causes it to produce a good lather. The lemon gives the compound the

property of removing rust and other stains, such as produced by fruit. The soapstone produces a consistency and toughness by which waste or quick dissolving of the soap in water is prevented.

The ingredients having been mixed, the compound is allowed to harden, and may then be cut into bars, cakes, or other shapes and packed for shipment and sale.

What we claim is—

1. The herein-described compound for soap, consisting in mixing tallow, sal-soda, resin, milk, soapstone, and water of lime in about the proportions specified, and for the purpose set forth.

2. The herein-described soap compound, consisting of tallow, sal-soda, resin, milk, lemons, soapstone, and water of lime, substantially as and for the purpose specified.

In testimony whereof we affix our signatures in presence of two witnesses.

JAMES HOAGLAND.
BARNHARD ZIPFEL.

Witnesses:

J. R. KIRKUP,
JAS. MCKINLEY.
